UNITED STATES PATENT OFFICE

ALFRED F. MEYER, OF YALE, OKLAHOMA

FISHING RIG FOR DEEP WELLS

Application filed May 21, 1927. Serial No. 193,264.

This invention relates to improvements in fishing rigs for deep wells, and refers more particularly to an electrical generator unit connected through an electrical cable with a 5 magnet which is lowered into deep wells, such as oil wells, to clear the well of steel or iron obstructions such as drills which have broken during the drilling operation, iron slugs or other metallic obstructions 10 which hinder and delay drilling operations.

The novelty in the invention lies primarily in the use of an electrical generating unit for transmitting strong magnetic forces to a magnet which is lowered into the well, 15 and which draws to it any iron or steel obstruction in the casing.

Fig. 1 is a side elevational view of the apparatus with parts in section and parts broken away.

20 Fig. 2 is a plan view of the electric cable reel.

Fig. 3 is an enlarged detail of a single contact magnet.

25 Fig. 4 is an enlarged detail of a double contact magnet used at the end of the electrical cable, and

Fig. 5 is a plan view of the mechanism shown in Fig. 1.

Referring to the drawings, at 1 is diagrammatically shown an engine which is direct connected to a generator 2, by means of a shaft 3. Interposed in this shaft is a clutch 4 for disengaging the engine from the electrical generator. At 5 is shown a 35 cable reel and interposed in the wire connections between the generator and the reel is an ammeter 6, and shock coils 7. A derrick 8, positioned above the well, which is enclosed by the casing 9, is shown in reduced size relative to the equipment forming the subject matter in the present invention.

At 10 is diagrammatically shown a reel, upon which the sand line 11 is coiled. This 45 sand line passes over a shive or block near the top of the derrick, and is used for lowering and raising the magnet 12 in and out of the well.

The wire connections 13 and 14 between 50 the shock coils and the cable winch are con-

nected to brushes 15 and 16 upon the ends of the winch or reel, each of the brushes having connection with the two-wire cable 17, coiled upon the reel; thus the power from the generator is transmitted through 55 the shock coils to the brushes on the outside of the winch, and thence to the end of the cable 17.

The operation of the mechanism is briefly as follows: The motor or internal combustion engine 1 is run at the desired speed to drive the generator at a proper speed to produce the amount of electrical energy necessary to build up the desired magnetic force in the magnet 12. The engine being direct connected to the generator, drives the latter at a speed proper for the electrical energy required. This current is registered on the ammeter shown at 6. Shock coils 7 are interposed in the circuit to prevent excess load being imposed directly upon the generator. When a cone from a rock drill, or a broken fish-tail bit becomes lodged in the casing, the magnet 12, to which is attached the two-wire cable 17, is lowered into the casing, the cable 17 passing over a snatch block attached to the derrick to supply a fair lead for the cable into the casing. The weight of the magnet is supported, as suggested, by the sand line 11, which is used to lower and raise the magnet in and out of the casing. When the magnet has been lowered to contact the iron or steel obstruction in the casing, the electrical energy is transmitted to the magnet, setting up strong magnetic forces which cause the obstruction to be rigidly attached to the magnet. The sand line is then reeled in and the magnet and obstructing element are brought to the surface where the latter is removed from the magnet and the casing thereby cleared. Either a single contact or a double contact magnet may be used, as desired.

The operation of the reel upon which the sand line is coiled is preferably synchronized with the drive which reels in and pays out the electric cable mounted upon the reel 5. This drive is diagrammatically shown in the form of a shaft 18, and gear box 19, positioned at the opposite end of the winch.

or reel to that on which the ring connections are mounted. The shaft 18 is rotated through bevel gears from the main drive shaft 3 and is connected by bevel gears to the shaft upon which the reel 10 is mounted.

By the use of this mechanism a fishing job for a broken bit, iron slugs, or any other steel or iron obstruction, is made very simple. The unit may be mounted upon a conveyance, such as an automobile truck, in order that it may be transported from place to place as required.

It has been found to be a great time saver, and altogether satisfactory in removing obstructions from oil well casings which have heretofore caused serious shut down periods and delay in drilling operations.

I claim as my invention:

1. In a fishing rig for deep wells, the combination with a source of power, direct connected to an electric generator unit, of an electro magnet connected by electric cables to the generator, a reel upon which the cables are wound, insulated rings on the spool of the reel, brushes contacting the insulated rings and connected to the cables, and separate means for raising and lowering the magnet in the well.

2. In a fishing rig for deep wells, the combination with a source of power, direct connected to an electric generator unit, of an electro magnet connected by electric cables to the generator, a reel upon which the cables are wound, insulated rings on the spool of the reel, brushes contacting the insulated rings and connected to the cables, and separate means for raising and lowering the magnet in the well synchronized with the reel upon which the electric cable is wound, whereby the means for raising and lowering the magnet function simultaneously with the cable reel.

3. In a fishing rig for deep wells, the combination with a source of power direct connected to an electric generator, of a magnet connected by electric cables to the generator, a reel upon which the cables are wound, serving to pay out and reel in the cable as the magnet is lowered and raised in the well, separate means for raising and lowering the magnet, synchronized with the reel upon which the cable is wound, current transmitting means arranged between the generator and the cables including ring connections on the spool of the cable reel, brushes contacting with the rings and connected with the generator for maintaining a continuous circuit.

4. In a fishing rig for deep wells, the combination with a source of power direct connected to an electric generator, of a magnet connected by electric cables to the generator, a reel upon which the cables are wound, serving to pay out and reel in the cable as the magnet is lowered and raised in

the well, separate means for raising and lowering the magnet, synchronized with the reel upon which the cable is wound, current transmitting means arranged between the generator and the cables including ring connections on the spool of the cable reel, brushes contacting with the rings and connected with the generator for maintaining a continuous circuit, and shock coils interposed between the generator and the cable reel.

ALFRED F. MEYER.
